FIRE EXTINGUISHER MEANS

David Moffat Myers, Larchmont, N. Y.

Application December 12, 1946, Serial No. 369,785

1-Claim. (Cl. 299—96)

The invention relates to liquid dispensing means, particularly fire extinguisher means employing a chemical extinguishing liquid such as carbon tetrachloride, and it is concerned more especially with an attachment for converting a container for such liquid into an extinguisher means whereby the liquid contents may be delivered and projected a considerable distance. Ordinarily, containers for such liquid are in the nature of tin-plate cans of quart or larger size having a screw-cap cover or seal on a neck of the container through which neck the fluid may be emptied when the screw-cap is removed.

The invention has for an object an attachment or substitute closure plug for the usual screw-cap of such containers whereby the can is converted into an effective fire-extinguishing means, the original cap being discarded.

A further object of the invention is to provide a novel cap member designed to replace the standard screw-cap of such containers.

It has been found that after more or less extended periods of time certain manually-operated pumping types of fire extinguishers occasionally stick and bind sufficiently to render the extinguisher useless in an emergency; and it is another object of the invention to provide a fire extinguisher attachment having no moving parts in the liquid, thereby eliminating much of the usual difficulty resulting from corrosion of moving parts.

Still another object of the invention is to provide an extinguisher which will eliminate the inconvenient necessity of refilling, as in the case of the usual type of fire extinguisher after its charge of fluid is exhausted, the novel attachment requiring merely the throwing away of the empty can and the application of the attachment to a new and full can.

The invention has for an object, also, to provide a construction which will prevent spillage as well as evaporation of the contents of the can and also contact of the liquid with the means for providing pressure thereon.

The novel attachment, moreover, obviates the purchase of an expensive and costly container forming part of the usual type of hand-operated, chemical fire extinguisher, it being necessary merely to purchase the chemical in an ordinary can and attach the novel device thereto to convert the same immediately into an effective fire extinguisher.

In carrying out the invention, the usual sealing cap which is threaded on the neck of a can of the liquid is discarded and there is substituted

therefor a novel closure member or plug. This plug comprises a cap member designed to fit over the said neck and includes a head portion to seal the container and through which head portion extend means such as an air pipe with external bulb for introducing air under pressure into the container.

A further means, such as an ejector pipe, extends substantially to the bottom of the container passing through the said plug and terminates externally in a nozzle for discharging the contents of the container when the air under pressure is applied. Both the air pipe and the ejector pipe are carried by said head portion and sealing means are provided therein to prevent discharge of the liquid except when required. Means are further provided for rapidly and conveniently opening these passageways when the liquid is to be discharged.

The nature of the invention, however, will best be understood when described in connection with the accompanying drawing, in which:

Fig. 1 is a plan view and Fig. 2 a front elevation, partly in vertical section, of the novel attachment applied to a can.

Referring to the drawing, the novel attachment is shown in the nature of a cap member 33 threaded to fit on the correspondingly threaded neck 34 of a container 30, the latter embodying the usual tin-plate can of quart or larger size containing the desired liquid to be discharged, for example, a fire-extinguishing liquid or chemical such as carbon tetrachloride. The usual cap (not shown) furnished with such can is to be discarded and replaced by the cap 33 which is screwed down to form an air-tight joint. This cap has associated with it either integrally or as a separate element a head portion 32 immediately beneath the top of the cap. The said head portion and cap are bored through to afford passages for receiving an air pipe 37 and an ejector pipe 38, respectively. These pipes may be soldered to the closure member or be otherwise secured thereto to effect a sealed joint therewith.

The former pipe 37 extends merely into the cap member flush with the underface of the head portion and is designed to introduce air into the container 30 as by means of a valved rubber bulb 29 of well-known construction such as utilized in atomizers and the like. Ejector pipe 38, however, is of a length to extend into the container 30 substantially to the bottom thereof for delivering liquid from the container when air under pressure is applied through the pipe 37. The discharge is effected through a nozzle 31 at the

outer end of the pipe 38, the nozzle portion sloping upwardly to provide for drainage of the liquid back into the container after the extinguisher has been in use.

In order to prevent flow of the liquid into the bulb 29, which might destroy or damage the same, a hand-operated valve 28 is provided in the pipe 37 between said bulb and the cap; and a closed tip or the like 25 is fitted over the nozzle to seal the latter when the extinguisher is not in use. When it is desired to operate the extinguisher, tip 25, of course, is to be removed from the nozzle and the valve 28 is turned to permit air from the bulb 29 to enter the container through pipe 37.

An arrangement is indicated, furthermore, for removing temporarily the tip for the nozzle automatically with the opening of the valve in the air supply pipe. Thus, tip 25 is swiveled to the end of a stiff wire or link 26 which in turn is swiveled to the operating handle or arm 27 of the valve 28 in the air supply pipe, so that when the valve is turned to open the communication between bulb 29 and container 30, for example, by moving into the broken-line position, tip 25 will be drawn away from the nozzle 31 which will then be clear for discharge of the liquid from the container 30.

In this embodiment, also, the head portion 32 is constituted as an element separate from the cap 33 and is in the nature of a flanged plug fitting into the neck 34 of the container and supported on its rim. Over this plug is the flange 35 of the cap so that when the latter is screwed down on the neck 34 a tight seal will be afforded for the container. The central opening 36 in the top or flange portion of the cap admits the pipes 37 and 38 to the head portion so that this portion with the pipes need not rotate in sealing the container, it being necessary merely to screw down the cap portion to force the flange of plug or head portion 32 tightly against the rim of neck 34.

With the arrangement hereinbefore described, it is possible to convert quickly an ordinary can of the liquid into a very effective fire extinguisher, with which it is possible to throw a stream some 15 feet from the container upon compressing and working the bulb in the usual manner to supply air under pressure over the liquid. When the contents are exhausted, it is necessary merely to unscrew the attachment and apply the same to a further can.

The attachment may be constructed such that there will be no moving parts normally in contact with the liquid and subject to corrosion, nor will the bulb be contacted by the liquid at any time; and leakage and/or evaporation of the contents during storage is insured against in the provision of the sealing means associated with the pipes. The novel attachment is of inexpensive construction and is readily and quickly applied without the use of any tools.

I claim:

Liquid-ejecting means and substitute closure member for the sealing cap of a container, adapted for dispensing a fire-extinguishing liquid from the said container through the neck thereof, comprising a cap member designed to fit over the said neck and including a head portion, an air pipe extending through said head portion having means external the container for introducing air under pressure therein, and an ejector pipe extending through the head portion substantially to the bottom of the container and terminating externally thereof in a nozzle for discharging the contents of the container when air is introduced through the air pipe, a cap member normally sealing the nozzle and a valve element normally sealing the air pipe, together with means connecting the cap and valve element for removing simultaneously the cap with the opening of the valve.
